UNITED STATES PATENT OFFICE.

AUGUST HAGER, OF BUFFALO, NEW YORK, ASSIGNOR TO HIMSELF, LUCAS H. VAN ALLEN, AND SAMUEL F. COLT, OF SAME PLACE.

FREIGHT-CAR.

SPECIFICATION forming part of Letters Patent No. 674,357, dated May 14, 1901.

Application filed February 19, 1901. Serial No. 47,946. (No model.)

To all whom it may concern:

Be it known that I, AUGUST HAGER, a citizen of the United States, residing at Buffalo, in the county of Erie and State of New York, 5 have invented certain new and useful Improvements in Freight-Cars, of which the following is a specification.

My invention relates to a car chiefly adapted for carrying grain, coal, or similar material 10 and having an opening through which the material may be easily unloaded which is closed by a door having flanges interlocking with a flange around the opening to prevent leaking; and the main object of the invention is 15 to form, arrange, and fit the door to the opening in the car in such manner as to absolutely prevent any leakage of the material around the door when closed.

The invention further relates to certain details of construction.

For a full understanding of the merits and advantages of the invention reference is to be had to the accompanying drawings and the following description.

25 The invention is susceptible to various changes in the form, proportion, and minor details of construction without departing from the principle or sacrificing any of the advantages thereof, and to a full disclosure of 30 the invention an adaptation thereof is shown in the accompanying drawings, in which—

Figure 1 is a side elevation of a freight-car equipped with my improved device and showing the doors in open position. Fig. 2 is a 35 section on line *a a*, Fig. 1, showing the doors open. Fig. 3 is a bottom plan view of a fragment of a car, illustrating two of the doors and their operating mechanism. Fig. 4 is a section on line *b b*, Fig. 3. Fig. 5 is a 40 detached fragment of a car, showing the ratchet mechanism for opening and closing the doors. Fig. 6 is a section on line *c c*, Fig. 3. Fig. 7 is a detached top plan view of one of the doors.

45 In referring to the drawings in detail like numerals designate like parts.

In the preferred adaptation of the invention shown in the drawings, 1 represents the body of a freight-car, which is provided with 50 the trucks 2. An opening or openings 3 is arranged in the bottom 4 of the car, and this

opening, which is rectangular in shape, is surrounded by metal plates 5, which are fastened to the upper surface of the bottom by screws or bolts 6 and have portions 7, which 55 bend or curve downward at an angle to the body of the plate to form flanges. These flanges 7 extend entirely around the opening and are separated sufficiently from the edges or walls of the openings to leave spaces or 60 pockets 8. The door 9 is preferably of a similar rectangular form to fit the opening 3, and metal plates 10 are secured to the under surface of the door by screw-bolts or other fastenings 11. The outer portions 13 of these 65 metal plates are bent or curved upwardly at an angle to form flanges, which surround the edges of the door and are sufficiently separated from the door edges to leave spaces or pockets 14. The flanges 7 and 13 and the 70 pockets 8 and 14 are arranged so that when the door is in closed position the flange 7 seats or fits in the pocket 14 and the flange 13 fits in the pocket 8, thereby securing the edges of the door to the edges of the opening 75 in the car by interlocking flanges, which close the space between the door edges and walls of the opening, and thus prevent leakage of the material and also interlock the door edge to the walls of the opening at all points. 80 Four of these openings are preferably formed in the car-bottom, being arranged in pairs, and a like number of doors are preferably employed.

The doors are preferably hinged to the bottom at one end by hinges 15 and are locked in their closed position at the opposite end by bolts 16, which are slidably supported between a transverse beam 17 and the car-bottom. These bolts are preferably formed of 85 a flat strip of metal and provided with elongated slots 18, through which supporting-pins 19 are passed.

Means are provided for opening and closing the doors from the car side, which preferably consist of a shaft 20, rotatably supported from the car, a chain or rope 21, connected at one end to an eyepiece 22, attached to the door and connected at the opposite end to and winding upon the shaft 20, a ratchet-wheel 23 upon the shaft, a pawl 24, adapted to engage with the teeth in the ratchet-wheel, 95 100

and a handle 25 for turning the shaft. Two of these shafts are preferably employed, one for each pair of doors and each extending transversely across the car and being attached by a separate chain or rope to each of the two doors which it operates, so that the rotation of each shaft will either open or close two doors simultaneously.

The main advantages are that leakage is absolutely prevented when the doors are closed, owing to the mortise-and-tenon connections, the cars can be easily unloaded, and the doors are flush with the bottom when closed, thereby presenting a uniformly level and even floor.

Another great advantage is that box freight cars equipped with my improvement can be loaded with coal, shipped to one portion of the country, easily and quickly unloaded and cleaned, and then reloaded with grain or similar material or with other freight requiring an inclosed car, and do not need to be returned empty, as coal-cars generally are at the present time.

I claim as my invention—

1. A car having an opening and a door for

closing said opening; said car and door having oppositely-extending flanges and pockets to receive the flanges.

2. A car having an opening, a pocket surrounding the opening and a flange separating the opening from the pocket, and a door fitting in the opening and having a pocket to receive the flange of the car and a flange fitting in the pocket surrounding the opening. 35

3. A car having an opening in its bottom, metal plates surrounding the opening and having downwardly-extending flanges projecting in the opening, a door fitting the opening, metal plates secured to the door and having upwardly-extending flanges; the downwardly-extending flanges being adapted to fit between the door edge and the upwardly-extending flanges and the upwardly-extending flanges being adapted to fit between the 45 downwardly-extending flanges and the walls of the opening when the door is in its closed position.

AUGUST HAGER.
